Patented Apr. 25, 1922.

UNITED STATES PATENT OFFICE.

SIGURD HANSEN, OF SAN FRANCISCO, CALIFORNIA.

HARPOON.

1,414,084.

Specification of Letters Patent. Patented Apr. 25, 1922.

Application filed June 10, 1920. Serial No. 387,853.

To all whom it may concern:

Be it known that I, SIGURD HANSEN, a citizen of the United States, residing at the city and county of San Francisco and State 5 of California, have invented a new and useful Improvement in Harpoons, of which the following is a specification.

This invention relates to a harpoon, and especially to the bomb carrying type employed by whalers and the like.

One of the objects of the present invention is to provide a harpoon for whaling and the like which is simple in construction and exceedingly substantial for the purpose required; further to provide flukes, and means for automatically extending the same after the harpoon has entered, and especially when a pull is exerted.

Another object of the invention is to provide a simple connection which permits ready removal or detachment of the bomb, and in conjunction therewith a firing mechanism which will insure firing of the bomb a moment after entrance and then only.

25 Further objects will hereinafter appear.

The invention consists of the parts and the construction, combination and arrangement of parts as hereinafter more fully described and claimed, having reference to the 30 accompanying drawings, in which—

Fig. 1 is a side elevation of the harpoon.

Fig. 2 is a plan view of Fig. 1, showing the bomb removed.

Fig. 3 is an enlarged detail section of the 35 bomb and the firing mechanism employed.

Referring to the drawings in detail, A indicates in general a harpoon consisting of an elongated bar 2, which is cylindrical in cross section. Formed on the forward end of the 40 bar is a threaded extension 3, and adapted to be attached thereto is a bomb 4 of suitable construction. Formed in opposite sides of the bar, near the forward end, is a pair of slots 5, and pivotally attached in the forward end of said slots upon pins 6 is a pair 45 of flukes 7, which are adapted to be automatically projected by springs 8. Formed on the underside of the bar, and extending approximately from end to end thereof, is a rope channel 9, and formed at the extreme 50 rear end of the bar is a cross slot 10 with which the rope channel communicates. Extending crosswise of the slot and secured to the bar is a pin 11, and secured thereto by 55 means of an eye 12, or other suitable lash-

ing, is a rope 14 to which the harpoon is attached.

The bomb here shown is cone-shaped and pointed and is provided with an interior chamber 15, which is adapted to be charged 60 with black powder or any other suitable explosive. This charge is fired by a time fuse 16, which in turn is ignited by a pistol or a revolver cap 17 and a firing pin 18. The firing mechanism is supported in the forward end of the harpoon and projects through the threaded extension 3, a central passage or chamber 19 being provided for the reception of the firing mechanism as a whole. The firing mechanism consists of a 70 cylinder 20, which is threaded at its forward end, as at 21, and thereby secured in the central passage when inserted. This cylinder is also interiorly threaded for the reception of a firing block 22 and a fuse securing sleeve 23. The firing block 22 is provided with a central passage 24, which is penetrated by the firing pin 18 when this is projected, and a cartridge 17 is adapted to be inserted between the firing block and the 75 sleeve 23 where it is adapted to be impinged or struck by the pin 18, said pin 18 being projected by a spring 25 interposed between the end of the cylinder 20 and a collar 26, formed on the firing pin. The rear end of 80 the firing pin is provided with two perforations 27 and 28 for the reception of a wire 29. This wire is passed through an opening 30 formed in the bar and is then carried forward to a pin 31, which is lashed or otherwise secured to the bomb proper as indicated at 32.

One of the features of the present invention is to provide a harpoon which has a greater range than the most standard forms 95 employed today, and which will not fire upon impact, but only after the harpoon has entered. A long range is obtained and greater accuracy in shooting by presenting a harpoon which may be likened unto a 100 spear, that is it consists of a long cylindrical bar 2, which is provided with a comparatively heavy head member presented by the bomb 4. This design and shape lowers the head resistance to a minimum when the harpoon is in flight and therefore materially 105 increases the range and accuracy. The firing of the bomb here shown cannot take place except after the harpoon has entered. This is due to the fact that the pin 31 is 110

ashed to the forward end of the bomb. This pin tears away as the harpoon enters and thereby slackens the wire 30. This wire is threaded through the perforations 28 and 5 29 and holds the firing pin in extended position. The slackening of the wire, as the harpoon enters after the lashing 32 has been broken, releases the firing pin and permits the spring 25 to project the same. The 0 cartridge is in this manner exploded and the time fuse ignited and as this may be regulated to fire the main charge within the bomb at any time desired, it should be obvious that explosion will not take place 5 until the harpoon has become thoroughly embedded in the whale.

In actual practice the harpoon is placed in the muzzle of the gun, the rope or cable 14 being extended forwardly through the 0 rope channel 9 and then led to a long coil placed in front of the gun. The flukes 7 are folded inwardly against the spring tension and therefore lie flat against the main body of the harpoon when this is inserted 5 within the gun muzzle. They similarly remain flat or folded while the harpoon is in flight due to momentum and the air pressure exerted and only have a tendency to become projected after the harpoon has entered and 0 particularly when a pull is exerted by the whale.

The entire structure shown is exceedingly simple and substantial in design, and breakage should therefore be reduced to a minimum. The loaded bomb can be easily applied and removed whenever required and similarly the firing mechanism as this is also removable with relation to the harpoon proper.

0 While certain features of the present invention are more or less specifically illustrated, I wish it understood that various changes in form and proportion may be resorted to within the scope of the appended 5 claims, similarly that the materials and finish of the several parts employed may be such as the experience and judgment of the manufacturer may dictate or varying conditions may demand.

0 Having thus described my invention, what I claim and desire to secure by Letters Patent is—

1. A harpoon bomb comprising a hollow explosive containing head, a cylindrical 5 shank formed to fit the barrel of an impelling gun and a screw threaded connection between the head and the shank, a tube and a chamber formed in the shank within which the tube is secured, a firing block in the head 0 of the tube, a fuse projecting therefrom into the explosive containing head, a spring

pressed firing pin movable in the tube to engage the firing block, a pin disposed transversely exterior of the explosive containing head, means for lashing the pin, and a flexible connection between the pin and the firing pin, said transverse pin and flexible connection being automatically releasable upon contact of the transverse pin with the object fired at. 65 70

2. The combination in a harpoon bomb, of an explosive containing head and a removably attached impelling shank containing a firing pin and an actuating mechanism, a fuse projecting therefrom into a powder 75 chamber formed in the explosive containing head, a transverse pin carried by the explosive head and adapted to be lashed thereto, and a flexible connection between the transverse pin and the firing pin. 80

3. In a harpoon of the character described a bar of considerable length, a rope channel formed in the bar extending substantially from end to end, a cable adapted to pass through said channel and pivotally attached to the rear end of the bar, a removable explosive containing head adapted to be secured to the opposite end of the bar, means actuated by impact for firing the charge contained in said head, a pair of oppositely disposed channels formed in the bar at right angles to the rope channel, a pair of flukes pivotally mounted one in each channel, said flukes adapted to entirely enter the channels when folded and a spring secured in each 90 channel and engageable with the flukes to normally project the flukes. 95

4. In a harpoon of the character described a bar of considerable length, a threaded extension on the forward end thereof, a central 100 chamber formed in said extension and in the bar, a cylinder adapted to be screwed into said chamber, a time fuse carried by said cylinder, a firing block, a fuse and cartridge holder engageable with the firing block, a firing pin cooperable therewith, means for projecting the firing pin, a perforated extension on the firing pin, a wire insertable therein, a vertical passage formed in the bar through which the wire is adapted 105 to extend, a bomb adapted to be screwed on the central extension, a pin carried by the bomb and attached to the wire, and means for temporarily lashing the pin on the bomb. 110 115

In testimony whereof I have hereunto set my hand in the presence of two subscribing witnesses.

SIGURD HANSEN.
